HAIRPIN

Frank Gordon Hall, Chicago, Ill.

Application May 10, 1952, Serial No. 287,186

1 Claim. (Cl. 132—50)

2

This invention relates to improvements in hair pins and has for one object to provide a type of hair pin especially adapted for holding flat, circular curls commonly termed "pin curls," as formed on a woman's head.

A further object of my invention is to provide a hair pin especially adapted to be made of plastic material having sufficient flexibility to be readily opened by the fingers for application to the curl so that one does not need to use the teeth or finger nails to open it as is done with the well-known type of bobby pin.

Another object of my invention is to provide a hair pin of the character described above employing an external rib for spacing the formed curl from the scalp to promote ventilation for drying of the curl and also to aid in positioning the pin on the head of the user.

Other objects and purposes of the invention will appear from time to time as the following description proceeds.

The hair pin of the present invention constitutes an improvement over the type of hair pin disclosed and claimed in my application, Serial Number 268,359, filed January 26, 1952, now Patent No. 2,599,447.

My invention is illustrated more or less diagrammatically in the accompanying drawing, wherein

Figure 1 is a plan view of a hair pin constructed in accordance with my invention;

Figure 2 is a side elevation of Figure 1;

Figure 3 is a detailed section taken on line 3—3 of Figure 2;

Figure 4 is a plan view drawn to a smaller scale than the preceding figures and illustrating the manner in which my hair pin is applied to a circular or pin curl;

Figure 5 is a section taken generally on line 5—5 of Figure 4;

Figure 6 is an enlarged end view of the hair pin, showing the manner in which the central rib aids in positioning the pin when gripped between the finger and thumb of the user.

Like parts are indicated by like characters throughout the specification and drawing.

Referring to Figures 1 and 2, 1 is the long leg of the hair pin. It is joined by a continuous loop 2 to a short leg 3. In the form shown herein, the short leg 3 is inwardly depressed as at 4, toward the leg 1, thus centrally reducing the width of the pocket formed between the long and short legs. The outer or free end of the short leg terminates in a downwardly inclined portion 5, the end of which engages the long leg intermediate its ends. The arrangement is such that the

long end extends considerably beyond the end of the short leg so as to permit the finger of the user to exert pressure flatwise relative to the long leg without contacting the end of the short leg.

The long leg 1 is tipped at its extreme end with an enlarged tip to prevent scratching or cutting of a woman's scalp. The end of the short leg 3 terminates in a slightly upturned portion 7 to aid in applying the pin to the curl.

With the legs shaped as shown and described, the downwardly inclined portion 5 of the short leg defines a closed loop or pocket for the hair and the intermediate inwardly depressed portion 4 divides the pocket thus formed into two arcuately shaped areas indicated at A and B which are of substantially equal area.

As seen in Figure 1, both the long and the short legs are wider at their looped ends 2 and taper gradually toward their free ends.

The features hereinabove set forth are broadly shown and described in my aforementioned Patent No. 2,599,447.

Referring now more particularly to the novel features of the present invention, the pin is preferably made of a single piece of molded plastic. The legs 1 and 3, together with the spring loop 2, are formed with continuous, widened, substantially flat, inner body portions 9, 10 and 11 which generally define the shape of the two areas A and B. A centrally disposed, outwardly extending rib 12 is formed integrally with the flattened portion 9 of leg 1 and continues as an arcuate rib 13 about the loop 10, and thence as a continuing rib 14 along the upper surface of the flattened body portion 11 of the short leg 3. As will be seen in Figure 2, the bottom rib 12 is tapered in height toward the extreme end of the long leg 1 and the top rib 14 is tapered in height toward the extreme end of the short leg 3.

The rib portions 12, 13 and 14 just described serve to strengthen the pin against breakage and, in particular, to increase the tension on the spring loop effective to hold the two legs together when the device is in operation. This feature is of particular advantage where the pin is made of plastic material as it increases the strength of the pin without an undue increase in weight or thickness of the body of the pin, particularly in the area of the spring loop 2.

A further advantage of the ribbed construction is the arrangement whereby the lower rib 12 on the longer leg 1 serves to space the body of the pin, together with the curl, a substantial distance away from the scalp of the user, as shown in Figure 5, when the pin is in use, with

the coils of a curl secured within the looped areas A and B. This permits a freer circulation of air between the scalp of the user and the curl to aid in drying the hair in its curled condition.

A still further advantage of the novel ribbed construction is the fact that the rib serves as a guide when holding the pin between the fingers so as to indicate to the user when the pin is in proper position as it is being applied to the curl. This feature is particularly helpful in a device of this kind where so many of the curls are put up on the head by "feel" out of sight of the user. Even when a mirror can be used, it will be found more convenient to rely upon feel rather than sight for the proper application of the pin to the curl. Figure 6 shows the manner in which the rib serves as a guide when gripped between the finger and thumb of the user.

Although I have shown and described certain embodiments of my invention, it will be understood that I do not wish to be limited to the exact construction shown and described, but that various changes and modifications may be made without departing from the spirit and scope of the invention as defined in the appended claim.

I claim:

In a hair pin comprising long and short legs joined at one end by a continuous spring loop, the short leg being spaced from the long leg for the major portion of its length, and having a terminal portion inwardly inclined toward the long leg, an intermediate portion of said

terminal portion being normally held against the long leg by the tension of the spring loop to maintain said major portion of the short leg in spaced relation with the long leg, the extreme end of said terminal portion of the short leg being bent outwardly away from the plane of the long leg, the long leg extending beyond the end of the short leg a distance to permit flatwise pressure of the finger of the user upon said long leg without contact with the short leg, the combination of a continuous rib formed integrally with and extending centrally along the outer faces of said long leg, loop and short leg, the said legs, loop and rib being of sufficient flexibility to permit the legs to be readily spread apart by the fingers of the user, said rib being of maximum height adjacent the loop and tapering in height towards the free ends of the long and short legs, said hairpin being made of molded plastic material.

FRANK GORDON HALL.
